INVENTOR

UNITED STATES PATENT OFFICE.

SIMON HEITER, OF NEW YORK, N. Y.

DESIGN FOR A PARASOL.

SPECIFICATION forming part of Design No. 19,652, dated February 18, 1890.

Application filed December 5, 1889. Serial No. 332,738. Term of patent 3½ years.

To all whom it may concern:

Be it known that I, SIMON HEITER, a citizen of the United States, residing at No. 136 West 71st street, in the city, county, and State 5 of New York, have invented and produced a new and original Design for a Parasol, of which the following is a specification, reference being had to the accompanying drawings, forming part thereof.

10 Figure 1 is a side elevation of my newly-designed parasol, and Fig. 2 is the plan.

The top or cover of the parasol, ornamented as represented with my design, is of the ordinary contour. The design consists of an interrupted or broken band or bands around or

near the margin of such top or cover. The sections of the bands are indicated at B, the space between the ends C C of these sections being the same kind of surface as that of the other surrounding surface of the top or cover. 20

I claim as my invention—

The design for a parasol-top, the same consisting of the top or cover of the parasol having the interrupted marginal band, as shown and described.

SIMON HEITER.
